UNITED STATES PATENT OFFICE.

JONATHAN A. HUNT, OF SALEM, MASSACHUSETTS, ASSIGNOR TO FREDERICK L. EMERY, OF LEXINGTON, MASSACHUSETTS.

ROD-GRINDING MACHINE.

Application filed August 17, 1920, Serial No. 404,112. Renewed February 9, 1923.

To all whom it may concern:

Be it known that I, JONATHAN A. HUNT, a citizen of the United States, and a resident of Salem, in the county of Essex and 5 State of Massachusetts, have invented an Improvement in Rod-Grinding Machines, of which the following description, in connection with the accompanying drawings, is a specification, like characters on the 10 drawings representing like parts.

This invention relates to machines for pointing wires or rods and an object is to provide means for feeding said wires or rods from a mass to the forming member in 15 a single layer and in close formation without twisting or tangling. A further object of the invention is to provide means for removing the rods that have been ground or sharpened and for conveying the same to 20 predetermined points such, for example, as to other machines such as finishing machines.

The invention consists in the combination and arrangement of parts set forth in the 25 following specification and particularly pointed out in the claims.

In the accompanying drawings wherein is shown merely for purposes of illustration one embodiment of the invention;

20 Fig. 1 is a front elevation of the machine;

Fig. 2 is a plan view of the work-separating and feeding means, portions of the forming member herein a grinding wheel being shown in dotted lines while other 25 parts such as the mechanism for supporting and driving the feed rolls are removed to more clearly illustrate the rod separating and feeding instruments;

Fig. 3 is a vertical section taken on the 30 line 3—3 of Fig. 2;

Fig. 4 is a vertical section through one end of the finger supporting and raising means, this section being taken on the line 4—4 of Fig. 3;

Fig. 5 is a transverse section of the feed 45 wheel driving clutch taken on the line 5—5 of Fig. 2; and

Fig. 6 is a vertical detail section of the inner end of one of the guide fingers showing the detents or rod retarding means carried thereby.

In the drawings a frame is shown for supporting the various mechanisms of the machine. This frame preferably includes 50 front and back members 1 and 2 and side

members 3 suitably secured together. Mounted within said frame is a casing or housing 4 adapted to contain the work-forming member herein an abrasive grinding wheel 5, the latter being secured to an 60 arbor 6 journaled in bearing blocks 7, 7 at opposite sides of the grinder housing 4. The grinding wheel 5 is provided with a concave grinding face 8 of well known 65 form.

It is desirable that the grinding wheel be adjustable in order to compensate for the wearing down thereof and this adjustment is preferably such as to effect the movement of the axis of the wheel laterally or in a direction substantially at right angles to said axis. Any appropriate means may be employed for producing this result such, for example, as screws 9, herein two, pivotally connected at their upper ends as at 10 between the lugs 11 formed upon said housing. 70

The screws 9 are guided in lugs 12 formed upon the side members 3 of the frame and vertical movement is imparted to each of said screws hereby by nuts 13 constituting 80 bevelled pinions and adapted to rotate upon the lugs 12. Each of the nuts or pinions 13 is arranged to mesh with a bevelled gear 14 attached to a counter-shaft 15 and journaled to rotate in suitable bearings or lugs 85 16 projecting from the side frames 3. Secured to the opposite ends of the counter-shaft 15 is a second bevelled gear 17 in turn meshing with the driving gear 18 attached to a common operating shaft 19, the latter 90 arranged in bearings 20 in the side frames 3. An operating wheel 21 is attached to said shaft 19 whereby a rotary motion may be imparted thereto by the operator.

Means such as set screws 22 are provided 95 for securely holding the housing or casing in its adjusted position.

Lateral movement of the housing 4 in the direction of the axis of the grinder during the raising and lowering thereof may be, and 100 herein is regulated by suitable guide screws 25 mounted in the frames 1 and 2 and arranged to engage the faces of ribs 26 formed upon said housing.

Any suitable driving means may be provided for the grinder 4 and herein for this purpose I have shown in dotted lines a pulley 27 attached to the arbor 6, which pulley receives its power from any appropriate 105 source not shown.

The housing 4 for the grinder surrounds the greater portion of the periphery thereof so as to catch the grinding dust discharged from said grinder and in the present example a pipe 30 is shown having telescopic connection as at 31 with the bottom or lower portion of the housing so as to allow for raising and lowering thereof and this pipe is adapted to remove from the housing or 10 casing all dust accumulated therein.

In machines of the character described, the work is fed transversely of the face of the grinding wheel or work-forming member and preferably in substantially tangential relation thereto but at an angle to the axis of the grinder, the grinding operation being initiated at the end of the work at a point in the circumference in advance of the point of contact of the tangent with its circle, 15 the end of the work being moved, during the feeding operation, at an angle to but toward a radial plane passing through said point of contact. As the work, herein rods or wires, is advanced transversely of the 20 grinding face of the wheel, its ends will gradually assume the form of a point by reason of its gradual approach to said plane.

It is obviously within the scope and purpose of the invention to form either a chisel or a round point upon the ends of the rods but in the present example means for effecting the rounding of the points are shown, said means preferably including a plurality of saddles 32 and cooperating feed wheels 33. The saddles 32 have concave and herein resilient guiding surfaces 34 which coincide with the concave face of the grinding wheel. The cooperating faces of feed 35 wheels are likewise provided with resilient coverings 35 and these conform with the faces 34 of the saddles.

It is desirable, at times to vary the angle of approach of the rods or work with 45 respect to the grinding surface of the member 5 so that the taper or angle of the finished point may be long or short and in the present example this adjustment is provided for by mounting the saddles 32 and 50 their cooperating feed wheels upon a suitable work table 36 to which lateral, longitudinal or transverse movement may be imparted to vary its relation to the work member as will hereinafter be described.

The table 36 has an opening 37 through 55 which the housing and grinding wheel are adapted to protrude in order that the work carried by said table or saddles may be brought into contact with the grinding face 60 of said wheel. The work table 36 is inclined at an angle to a horizontal plane inclining downwardly toward the left in Fig. 1 and said table is preferably mounted so that this angle may be varied from time 65 to time as need requires. The saddles 32 are

mounted upon the table 36 within the opening 37 (see Fig. 3) and in such a manner that they may be adjusted longitudinally of said opening or of said table, or said saddles may be rocked slightly to cause the guiding surfaces thereof to more perfectly fit or conform to the coacting surfaces of the feed wheels 33. Appropriate means are provided for effecting the adjustment of said saddles longitudinally of the table, said means herein consisting of a key 38 which key is arranged to slide with said saddle and in a groove 39 extending longitudinally of the table 36 and substantially parallel with the opening 37. The key 38 may be attached in any appropriate manner to said saddle but as shown it extends through a groove 40 formed in said saddle. An adjusting screw 41 is secured at each side of the saddle in lugs 42 projecting laterally from opposite faces thereof, said screws 41 being adjacent to the key 38 and arranged to engage the upper surface of the table 36 with which they are held in contact by screws 43, the latter being mounted in said lugs 42 and having screw-threaded engagement with said table 36.

By adjusting the positions of the screws 41 in said lugs in conjunction with the screws 43, the end of the saddle or saddles containing said screws may be slightly raised or lowered and finally secured in their adjusted positions by said screws 43. The opposite ends of the saddles are also adjustably arranged with respect to the upper surface of the table 36 herein by screws 44 mounted in screw-threaded engagement with lateral lugs 45 on said saddles, said screws resting against the upper face of the table 36. If desired the screws 44 may be maintained in contact with the table by screws 46 which are arranged to extend through said lugs 45 and into screw-threaded engagement with said table. By the means described the cooperating surfaces of the saddles and their feed wheels may be adjusted so as to secure the most effectual relation.

It is desirable to provide for the adjustment of the saddles longitudinally of the table 36, the saddle nearest to the grinding wheel being adjustable to compensate for the reduction in diameter of said wheel due to wearing down thereof while the other saddle is made adjustable to accommodate rods of varying lengths. There are occasions when the adjustment particularly of the saddles nearest to the grinding wheel should be very fine and gradual. Therefore appropriate means for effecting such an adjustment are provided, the present example including an adjusting screw 46 (see Fig. 1) arranged in screw-threaded engagement with a bracket 47 and with its inner end engaging the edge of the plate 48 on which

rests the left or lowermost end of the table 36.

The bracket 47 has ears 49 through which passes a shaft 51, the latter being supported in suitable bearings such as 52 on the frame 3. The shaft 51 is provided with cams or eccentrics 54 arranged to engage the plate 48 and an operating lever 55 is attached to one end of said shaft whereby said shaft 10 may be rotated when it is desired to raise the end of said work table and remove the ends of the rods that are being pointed from the grinding wheel.

When a more extensive movement of the 15 saddles than is possible with the screw 46 is required the screws 43 and 46 may be removed and the saddle and its key 38 moved along the groove 39 and the screws 43 and 46 inserted in other holes provided 20 in the top of the work table for this purpose.

The right hand end of the table 36, as viewed in Fig. 1, is also adjustable vertically herein by means of screw-threaded rods 56 pivotally attached at 57 to the under side of said table, the lower ends of said screws engaging the plates 58 wherein they are held in their adjusted position by check nuts 59 (see Fig. 1). The plates 58 30 are also slotted at 63 to receive the screws 62 thus allowing a limited adjustment of the plates without necessitating the movement of the screws to other holes.

From the foregoing description it will 35 be seen that universal adjustment of the table 36 is possible.

In machines of the type shown considerable difficulty has been experienced in feeding rods to the grinding wheel by reason of the fact that rods of considerable 40 length become twisted about each other and clog the feeding devices for the machine but in the present machine this has been overcome by providing a plurality of 45 sets of feed members, each including a saddle and feeding wheel and arranged to have independent adjustment longitudinally of the work table, as previously described, so that they may engage the rods 50 at such points as to prevent any twisting or entangling of the rods.

The feed wheels 33 as well as the saddles 32 are independently adjustable, they being mounted upon a shaft 64 journalled to 55 rotate in suitable bearings such as boxes 65 vertically adjustable in slotted standards or brackets 66, the latter being carried by the table 36. The wheels 33 are keyed to said shaft but are capable of movement 60 longitudinally thereof. The shaft 64 receives its motion from any suitable source through a counter-shaft 68, the latter having a pulley 71 secured thereto and driven by a belt 72, the latter being arranged so 65 that upon the slight upward tilt of the

table 36 by means of the cams 54, said belt 72 will be slackened so as to prevent further movement of the shaft 51, thus stopping the feed of the rods to the grinding wheel.

Means are herein shown for adjusting the feed wheels 33 toward or away from the grinding surfaces of the saddles 32 especially when rods of large or small diameter are to be fed and obviously it is desirable 70 that the two or plurality of feed wheels be given simultaneous and equal movements so that the same amount of pressure will always be brought to bear upon all portions of the rods, thus insuring an equal feeding movement of the ends of the rods. For this purpose means are provided comprising screws 73 shown in dotted lines in Fig. 1, one being rotatable in each of the standards 66 and having screw-threaded engagement with the boxes 65. The screws are provided with bevelled gears 74 to mesh with bevelled gears 75 fast to a common driving shaft 76 arranged to rotate in bearings in said standards. A hand wheel 77 80 is attached to said shaft and serves as means for manually operating the shaft to raise and lower said boxes.

It is desirable that the rods be fed by the feed wheels in a single layer transversely of the face of the grinding wheel in order that each rod shall receive the same amount of grinding and that the grinding be uniform all around so as to bring the point exactly at the center of the rod. It is also desirable that the machine be automatic, that is that the rods be fed or separated from a mass and delivered to the feeding means in a single layer. Therefore in the present example means are provided for containing a mass of rods, said means consisting of a chute-like member 78 mounted upon the table 36 and including side members 79 and 80 and a bottom 81. The bottom 81 is preferably pivoted between the side members 79 and 80 at 82 (see Fig. 3) and means are provided as at 83 for securing said bottom in predetermined positions. The bottom 81 is arranged substantially 105 parallel with the table 36 and the rods in 110 the mass are placed upon said bottom and by reason of the inclination thereof downward toward the grinding wheel, said rods will have a tendency to slide toward the lower end of said container and even said 115 ends preparatory to being advanced to the grinder. The bottom 81 also inclines downwardly from the receiving end of the container toward the grinding wheel as shown most clearly in Fig. 3 and adjacent to the 120 inner or lower side of the said bottom are rod separating members 84, in the present example consisting of endless conveyors 125 herein chains arranged about sprockets 85 and 86 mounted respectively upon shafts 87 130

and 88 journalled to rotate in the side members 79 and 80. These shafts are arranged substantially parallel and one above the other, the lower shaft 87 being positioned 5 adjacent to and parallel with the axis of the pivot 82 of the bottom of said container so that teeth 89 formed upon the endless conveyors or chains, as they move upwardly will pass close to the pivoted side of said 10 bottom and as said bottom is inclined downwardly toward said conveyor, said rods will have a tendency to crowd against the chains and be picked up by the teeth thereof, said teeth herein being of a length at the most 15 no greater than the diameter of the rods composing the mass. The upper shaft 88 is placed somewhat nearer the grinding wheel than is the shaft 87 and the uppermost points in the peripheries of the chains 20 which pass over the sprockets mounted upon said shaft 88, are about on a level with the forward or receiving end of the saddle 32. Hence the runs of the conveyors which extend from sprocket to sprocket and particu- 25 larly the upwardly moving runs will be slightly inclined from the container toward the grinding wheel so as to prevent the rods which are picked up by the teeth 89 of said chains from falling back into the 30 container.

Any suitable form of chain may be employed for serving as the endless conveyors or separating means and the number of teeth and spacing of said teeth may be varied to 35 suit the particular needs of the machine. In the present example the type of chain known as the "silent" chain is employed and upon each of the links of this chain there are two teeth, said teeth being spaced 40 far enough apart to take in approximately three rods. All of the links of the conveyor chain are duplicates and are secured together so as to form a substantially continuous moving wall at the back of the rod 45 container, the teeth of said links forming substantially continuous ledges extending nearly the entire length of the container except at points where gaps in the series are provided for purposes hereinafter explained. The working runs of the chain travel upwardly as indicated by the arrow 50 *a*, Fig. 3 and as they pick up the rods from the mass shown at *b*, said rods will be elevated to a point substantially on the level 55 of the forward or receiving end of the saddles 32. There is, however, a gap between the highest point of delivery of the conveyor and the receiving end of the saddles, which gap is herein spanned by a 60 guide plate 90 which, at its inner end, extends to a point 90' flush with the receiving end of the guide surface of the saddle 32 and at its forward end said plate is recessed 65 at 91 to receive the conveyor chain. The recessing of said plate forms stripping

fingers 92 which extend over the shaft 88 and into gaps 93 (see Fig. 1) formed at intervals in the conveyor members 84. The upper surface of the plate 90 forms a tangent with the supporting surface of the conveyor members. Hence the rods that are carried upwardly by said conveyor members will be carried over the ends of the fingers 92 and be guided thereby onto the upper surface of said plate 90, said fingers 70 stripping the said rods from the teeth of the conveyor chains and preventing them from being carried down upon the back side of the conveyors and back to the mass by 75 the teeth 89.

To prevent more than one layer of rods from being carried by the teeth of said conveyor members to the plate 90, a wiper 94 is provided herein consisting of a strip of felt mounted upon a bar 95, said felt strip and said bar extending substantially the length of said rod mass container. The bar 95 is suspended by hangers 96 from a shaft 97 arranged to rock in bearings 98 in the sides 79 and 80 and a weighted arm 99 maintains said felt in yielding contact with the face of the conveyor members and thus 90 wipes off superfluous rods as said rods approach the upper end of the conveyor members. It is equally desirable to prevent piling of the rods as they are forced by the conveyor members along the top of the plate 90 to the feeding means including the wheel 33 and saddle 32, for which purpose I provide a row of fingers 100 preferably placed 100 directly above the fingers 92, and means are provided to space said fingers 100 from the fingers 92 a distance substantially equal to the diameter of the rods that are being fed upon the upper face of said plate 90, said means being such as to provide adjustment 105 for the rods of various diameters and also to permit said fingers to be raised when said rods become stuck for one reason or another in their passage from the conveyor members to the feed members. Obviously the same means employed for raising the shaft 64 may be employed in this connection but the means shown for accomplishing this purpose preferably include bars 101, 102 arranged between the sides 79 and 80 and supported at 115 their opposite ends by brackets 103, 104 (see Figs. 4, 5 and 6). The brackets 103, 104 have portions 105 which lie against the inner faces of the members 79 and 80 to 120 which the ends of the rods 101 and 102 are attached by screws 106 (see Fig. 6). Said brackets also have flanges 107 which extend over the side members 79 and 80 and contain 125 adjusting screws 108 adjacent their opposite ends to engage the edges of the members 79 and 80 and limit the downward movement of said brackets and the parts carried thereby. A shaft 109 is journalled in said brackets and carries at its opposite ends 130

eccentric cams 110 engaging suitable eccentric straps 111 attached to opposite sides of said rod mass container. An operating lever 112 is attached to one end of said shaft 5 and serves as means whereby said shaft may be rotated and through said eccentric and strap to effect the raising and lowering of the fingers 100.

Occasionally there is a tendency for one 10 end of a rod to jump ahead of the other while passing from the conveyor member to the feed wheel 33 thus causing said rods to enter between said feed wheel and the saddle 15 improperly aligned. To prevent this from happening means are herein provided consisting of detents 113, one of which is pivoted as at 114 to each of the upper fingers 100. The inner ends, that is the ends 20 of said detents nearest the feed wheel 33 are heavier than the opposite ends and cause said detent to drop down against the rods that are being fed therebeneath and thus retard the movements of said rods. Stop pins 115 are provided to prevent said detents 25 from swinging downwardly too far when said fingers 100 are raised by the eccentric 110 away from the rods.

The present machine is adapted to handle either long or short rods but when short rods 30 are being separated from the mass (and by short rods I mean exceptionally short rods which are of approximately the length of a small number, perhaps three talking machine needles) it is desirable that the fingers 92 35 and 100 be placed nearer together in order to prevent the short ends from dropping down and getting caught during the feeding operation. For this reason the fingers near the left-hand end of the conveyor 40 members, that is, the end containing the portions of the rods that are to be pointed, are placed quite close together, but beyond this toward the right of said conveyor members the fingers may be and herein are more 45 widely spaced. Furthermore during the separating and feeding of extra long rods, very often such rods are bent or sprung but during the separating and rolling process such bent portions are often straightened and the rods thereby lengthened and to facilitate this action, certain of the fingers 50 at the right-hand end of the conveyor members e. g. the last form are inclined slightly toward the right-hand side 55 of the container as will be seen by referring to Fig. 4. Consequently as said rods are moved along said fingers this arrangement tends to stretch said rods toward the right to their full extent.

Very often the mass of rods that are placed 60 within the rod container do not align one with the other at the left-hand end thereof although the inclined bottom 81 has a tendency to force said rods against the lower 65 end and so even up said ends but to insure

the proper aligning or evening of said rods at said left end, a guide member 116 is provided within said container against the side 79 thereof and this guide member has a portion 117 which inclines slightly toward the 70 right (see Fig. 4) and joins with a straight portion 118 which latter serves as a guide for the ends of the rods to properly position them as they approach and are picked up by the conveyor members. Thus any rods 75 which tend to project beyond the required distance when first placed within the container will be pushed back to properly align with the mass. The member 116 is also inclined downwardly toward the left as will 80 be seen by referring to Fig. 1, and this inclination has a tendency to hold the ends of the rods of the mass downwardly as they are forced into the container and against the conveyor members. 85

Various methods may be employed for operating the conveyor members but herein I preferably provide means operable from the shaft 64 whereby said conveyor means will operate only when said shaft 64 operates, thereby preventing the piling up of work in front of the feed wheels 33 should said feed wheels be stopped for any reason. In the present example I provide means for driving said conveyor mechanism including 90 a friction clutch 119 attached to one end of the shaft 64 and having manually operable means 120 for throwing said clutch out of operation if, for any reason, it is 95 desired to stop feeding the rods to the feed 100 wheels 33 without discontinuing the movements of said feed wheels. The clutch herein shown is of well known form and needs no further description. This clutch is arranged to cooperate with a sprocket 121 105 normally loose upon the shaft 64, said sprocket being operatively connected by means of a chain 122 with an idler sprocket 124 shown in dotted lines in Fig. 3.

In passing to said idler sprocket one run 110 of said chain, preferably the lower run thereof, is arranged to engage the teeth of a sprocket gear 123 attached to the end of the shaft 64, thus causing said shaft 64 to be rotated in a reverse direction to that of 115 said feed wheels 33.

It is often desirable to convey the rods which have been pointed from the present machine to other machines or to certain points of distribution and in the present example I have provided means for taking care of the rods as they are delivered by the rod feeding means 32 and 33, said means herein comprising a series of endless chains 125 arranged upon the back or delivery side 120 of the feeding means and extending over a sprocket 126 secured to a shaft 127 which is also arranged to rotate in suitable bearings upon the table 36. The chains 125 are provided with teeth 128 similar to the teeth 130

89 of the separating conveyor members and these chains are spaced similarly to the fingers 92 and 100. A guide plate 129 is interposed between the receiving ends of the 5 conveyors 125 and the delivery end of the saddles 32 to convey the completed rods to the teeth of said chains and said rods are maintained in single formation against the surface of said guide plate by fingers 130 10 supported in substantially the same manner as are the fingers 100 hereinbefore described. The fingers 130, however, are superimposed over the conveyors 125 which latter are arranged to travel over suitable guide plates 15 131 (see Figs. 4 and 5).

As a convenient method of disposing of the dust and dirt which is collected in the rod container from the rods that are handled thereby, said container is herein shown as 20 having a dust-pan 135 arranged beneath the lower shaft 87 of the conveyor means and this pan is connected by means of a pipe 136 with the main blower pipe 30 so that a suction will be created in the dust-pan 135 25 and thus remove all dust or dirt which may collect therein.

In the foregoing description the words "wires" and "rods" have been used indiscriminately in describing the work and it is 30 distinctly to be understood that neither word is used in a limiting sense and that the machine is capable of operating upon work which may reasonably fall within the scope of the word "wires" or that which might 35 be more accurately described as "rods," there being a wide variation in the diameter of the work which may be operated upon by the machine embodying this invention. Furthermore either round, hexagonal, square, 40 or numerous other polygonal shapes of rods may be handled by said machine, as well as short, medium or long rods.

While I have herein shown and described merely for illustrative purposes, a specific 45 embodiment of my invention and have disclosed and discussed in detail the construction and arrangement incidental to such disclosure, it is distinctly to be understood that the invention is limited neither to the mere 50 details or relative arrangement or parts nor to the specific application herein shown but extensive variations from the illustrations 55 may be made without departing from the principles thereof.

55 Claims:

1. A rod grinding machine comprising, in combination, a grinder, means including independently adjustable saddles and cooperating feed wheels to roll the ends of said 60 rods transversely of the face of said grinder, means to contain a mass of rods, and means to feed said rods from the mass simultaneously to said saddles.

2. A rod grinding machine comprising, 65 in combination, a grinder, means to roll said

rods transversely of the face of said grinder, a rod container, means in said container to even the ends of the rods that are to be ground, and means to convey said rods from said container to said grinder. 70

3. In combination, a grinder, means to feed rods transversely of the face of said grinder, a rod mass container, and means to separate rods from the mass and present them to said rod-feeding means, said separating means including a series of endless toothed conveyors. 75

4. In combination, a grinder, means to feed rods transversely of the face of said grinder, a rod mass container, means to 80 separate rods from the mass and present them to said rod-feeding means, said separating means including a series of endless toothed conveyors, and guide fingers inter-spaced with said conveyors. 85

5. In combination, a grinder, means to feed the work into contact with said grinder including upwardly inclined toothed conveyors, means to separate the work from a mass, and means including an upwardly and 90 inwardly inclined guide adapted to cooperate with said toothed conveyors in depressing and aligning the ends of the work that are to be ground. 95

6. In combination, a grinder, means to feed the work into contact with said grinder, a series of spaced toothed conveyors to convey the work from a mass to the work-feeding member, guide fingers arranged between said conveyors to maintain the work in a 100 single layer as it approaches the feeding means, and means on said fingers to retard the advancement of said work.

7. In combination, a grinding wheel, means to roll rods along a predetermined 105 angular path to said grinding wheel, means to separate the rods from a mass and advance them in single layer formation to said rod rolling means, including toothed conveyor means, and a wiper mounted in 110 yielding relation to said conveyor to remove superfluous rods from said conveyor.

8. In combination, a grinding wheel, means to roll rods along a predetermined angular path to said grinding wheel, conveyor means for separating rods from a mass and advancing them to the rod rolling means, and a resilient wiper to cooperate with said conveyor means to remove superfluous rods therefrom. 115

9. In combination, a grinder, means to roll rods transversely of and at a predetermined angle to said grinder, means to separate the rods of a mass into a single layer formation for rolling, said means including conveyors having teeth to support the rods substantially throughout their length and advance them to the rolling means, and a plurality of sets of guide fingers between said conveyors and the rod rolling means to 120 125 130

guide said rods from one to the other, one finger of each set being removable to provide access to the rods therebetween.

10. In a wire or rod pointing machine, the combination with means for feeding the wires or rods to the work member, of means to separate said wires or rods from a mass, means to advance said wires or rods to the feeding means, and means to remove slack from said wires or rods.

11. The combination with a forming member of means to advance wires in single layer formation from a mass to said forming member in a direction transverse to the median axial lines of said wires, and means to maintain said wires in parallel relation and in said single layer formation, said latter means including a guide member along which said wires are advanced and a series of spaced fingers to engage the upper face of the layer, a plurality of the fingers at one end of said series being inclined with respect to the remaining fingers of the series to remove the slack from said wires during the advance movement thereof.

12. The combination with a forming member of means to advance wires in single layer formation to said forming member, and means to maintain said wires in parallel relation and in said single layer formation, said latter means including a guide member along which said wires are advanced and a series of spaced fingers to engage the upper face of the layer, a plurality of the fingers engaging the portions of the wires adjacent to the ends that are to be ground, being disposed parallel with the direction of movement of said wires, the remaining fingers of the series being inclined with respect thereto to remove the slack from said wires during the advancing movements thereof.

13. The combination with a work-forming member of a plurality of saddles to guide the ends of wires across the face of said work-forming member, feed wheels respectively to roll the wires along the guiding surfaces of said saddles, and means automatically to separate the wires from a mass and cause them simultaneously to engage the receiving ends of said saddles.

14. The combination with a work-forming member of means to feed wires transversely of their length across the face of said work member, means automatically to separate wires from a mass and advance them in single layer formation and in a direction transverse to their length to the wire-feeding means, said separating and advancing means including parallel upper and lower guide members, and means to raise and lower said upper members with respect to said lower members.

15. The combination with a work-forming member, of means to feed wires trans-

versely of their length across the face of said work member, means automatically to separate wires from a mass and advance them in single layer formation and in a direction transverse to their length to the wire feeding means, said separating and advancing means including parallel upper and lower spaced guide members, means to vary the width of the spaces between said guide members to accommodate wires of different sizes, and means bodily to remove said upper guide members from their guiding positions.

16. The combination with a work-forming member, of means to engage wires at a plurality of spaced points and to roll said wires transversely of the face of said work-forming member, and means to separate wires from a mass and advance them in single layer formation simultaneously to said rolling means.

17. The combination with a work-forming member, of means to engage wires at a plurality of spaced points and to roll said wires transversely of the face of said work-forming member, and means to separate wires from a mass and advance them in single layer formation simultaneously to said rolling means, said means including guides to engage the upper and lower faces of said layer of wires and detents arranged at spaced points lengthwise of said wires to retard the advance movement of said wires.

18. The combination with a work-forming member, of means to feed wires in a direction transverse to their length, into engagement with said work-forming member, toothed conveyors to separate wires from a mass and stripping fingers to strip said wires from said conveyors and to guide them to the wire-feeding means.

19. The combination with a rod grinding member, of means to feed rods in a direction transverse to their length across the face of said rod grinding member, a rod mass container having guiding means for the rods inclined downwardly toward the ends to be ground of the rods to effect the evening of said ends, and means automatically to separate rods from the mass and to advance them to said rod-feeding means.

20. The combination with a rod grinding member, of means to feed rods in a direction transverse to their length across the face of said rod grinding member, a rod mass container having guiding means for the rods inclined downwardly toward the ends to be ground of the rods to effect the evening of said ends, said container also having an inclined wall adjacent the lower end thereof to even the ends of said rods, and means to separate rods from the mass in said container and to advance them in single layer formation to said rod feeding means.

21. A rod grinding machine comprising, in combination, a grinding wheel, means to

feed rods in a direction transverse to their length across the face of said grinding wheel, means automatically to separate rods from a mass and to advance them in single layer formation to said rod feeding means, and means to remove ground rods from said machine.

22. A rod grinding machine comprising, in combination, a grinding wheel, means to feed rods in a direction transverse to their length across the face of said grinding wheel, means automatically to separate rods from a mass and to advance them in single layer formation to said rod feeding means, and means to remove ground rods from said machine in single layer formation and to maintain said rods in parallel relation during the removal thereof.

23. A rod grinding machine comprising, in combination, a grinding wheel, means to feed rods in a direction transverse to their length across the face of said grinding wheel, means automatically to separate rods from a mass and to advance them in single layer formation to said rod feeding means, and means to remove rods that have been ground from said machine in single layer formation and to maintain said rods in parallel relation during the removal thereof, said rod removing means including a plurality of spaced endless conveyors having lugs upon the rod engaging faces thereof to engage and advance said rods, and means to engage the upper sides of said rods to maintain them in contact with said lugs.

24. In combination, a work member, means to feed work to said work member including a series of separated toothed conveyors, a work mass container having an adjustable bottom arranged to incline downwardly toward said conveyors, and a series of fingers secured to the lower edge of said adjustable bottom within the spaces between said conveyors, said fingers being movable with said bottom and adapted to determine the projection of the teeth of said conveyors into the work mass.

25. In combination, a work member, means to feed work to said work member including a series of separated toothed conveyors, a work mass container having an adjustable bottom arranged to incline downwardly toward said conveyors, and a series of fingers secured to the lower edge of said adjustable bottom within the spaces between said conveyors, said fingers being movable with and relatively to said bottom and adapted to determine the projection of the teeth of said conveyors into the work mass.

26. In combination, a work member, means to feed work to said work member including a series of separated toothed conveyors, a work mass container having a pivotal work guiding member inclined downwardly toward said conveyors, means

to secure said guide member in predetermined angular positions, and a series of fingers secured to said guide member to move with and relatively thereto, said fingers constituting stops for the work mass. 70

27. A rod grinding machine comprising, in combination, a grinder, means to feed work to said grinder, means including a series of toothed conveyors to remove work from said grinder, and means to guide the 75 work from the grinder to said conveyors including sets of cooperating relatively movable guide members.

28. A rod grinding machine comprising, in combination, a grinder, means to feed 80 work to said grinder, and means including a series of spaced toothed conveyors to remove the work from said grinder, said conveyors being arranged relatively nearer together adjacent to the ground ends of the 85 work.

29. In combination, a work member, means to feed work in single layer formation to said work member, a guide member along which the work may be fed, guide 90 fingers arranged above said guide member, and means pivoted upon said guide fingers with their free ends extending forwardly into engagement with the work to retard the advance of said work. 95

30. A rod grinding machine comprising, in combination, a grinder, means to feed rods past and in contact with said grinder, a guide arranged at the delivery end of said feeding means, toothed conveyors to remove rods from said guide, and guide fingers arranged to guide rods from said feeding means upon and along said guide into engagement with the teeth of said conveyors. 100

31. A rod grinding machine comprising, in combination, a grinder, means to feed rods past and in contact with said grinder, a guide arranged at the delivery end of said feeding means, toothed conveyors to remove rods from said guide, guide fingers arranged to guide rods from said feeding means upon and along said guide into engagement with the teeth of said conveyors, and means to raise said guide fingers to provide access to the work. 105

32. In combination, a work member, means to feed the work to said work member including a toothed conveyor, an adjustable work mass support inclining toward said conveyor and guides adjustably arranged 110 with respect to said work mass support to determine the projection of the teeth of said conveyor into the work mass.

33. In combination, a work member, a work mass container, means to feed the work in substantially parallel relation from said work mass container to said work member including an endless toothed conveyor for engaging and advancing the ends of the work that are to be operated upon a work 125 130

mass support to guide said work to said conveyor with the work ends thereof in proper alignment and spaced members at the rear of said work mass support to vary 5 the extent of projection of the teeth of said conveyor into said mass.

34. A rod pointing machine comprising, in combination, a grinder, means to engage rods at a plurality of spaced points in their 10 length and advance them in parallel relation to said grinder and means including a rearwardly and laterally inclined support to guide said rods to said rod advancing means with the work ends in alignment.

15 35. A rod grinding machine comprising, in combination, a grinder, means to roll the rods transversely of and in contact with the face of said grinder, means to present said rods to said rolling means in single layer 20 formation and separate means to remove ground rods from said machine without changing their formation.

36. In a grinding machine, rod feeding means including at least one upwardly inclined toothed conveyor, a rod support arranged to incline downwardly from its receiving end toward said feeding means in increasing degrees as it approaches said feeding means, and means to vary the projection of the teeth of said conveyor into 25 the mass of rods on said support.

37. In a grinding machine, rod feeding means including at least one upwardly inclined toothed conveyor, a rod support arranged to incline downwardly toward said 30 toothed conveyor and laterally toward the end of the work to be ground and an inclined guide at the lower side of said support to even the ends to be ground of said rods as they approach said feeding means. 35

In testimony whereof, I have signed my name to this specification.

JONATHAN A. HUNT.
